UNITED STATES PATENT OFFICE.

FREDERICK W. COLE, OF NEWTON HIGHLANDS, MASSACHUSETTS, ASSIGNOR TO GAME-WELL FIRE ALARM TELEGRAPH CO., OF NEWTON UPPER FALLS, MASSACHUSETTS, A CORPORATION OF NEW YORK.

BINDING-POST.

1,210,764.

Specification of Letters Patent. Patented Jan. 2, 1917.

Application filed November 24, 1915. Serial No. 63,322.

To all whom it may concern:

Be it known that I, FREDERICK W. COLE, a citizen of the United States, residing at Newton Highlands, in the county of Middlesex and State of Massachusetts, have invented an Improvement in Binding-Posts, of which the following is a specification.

The present invention relates to binding-posts.

10 The object of the invention involves improvements in construction whereby a terminal portion of the wire may be arranged on a seat coextensive with the diameter of the post, and impinged by the binding-screw 15 for a considerable length, thus to provide a long frictional bearing between the screw and wire, and such impingement of the terminal portion may be of substantially the same degree of pressure throughout its 20 length, and very severe, without cutting or injuring the wire and the wire is positively held from being moved about the longitudinal axis of the body with a tendency to turn the screw and loosen the wire, and also from 25 being withdrawn.

In the drawings, wherein there has been illustrated the preferred embodiment of the invention; Figure 1 is a side elevation. Fig. 2 is a vertical section on line 2-2 of Fig. 1. 30 Fig. 3 is an enlarged vertical section of the body of the post.

In the drawings, 10 designates a base plate to which the binding-post is attached. The binding-post initially comprises a substantially cylindrical body of metal 12, the upper end of which is tapped to provide an internally threaded substantially cylindrical screw-receiving socket 13, having a flat bottom 14. The body 12 is pierced diametrically at the bottom of the socket 13, to provide aligned holes 15, 15, to receive a terminal portion 16 of the wire. The holes 15, 15, being located at the bottom of the socket, it will be observed that a horizontal plane tangential to their bottoms is substantially in the same plane with the bottom of the socket 13. This especial construction has been found to be particularly efficient since it provides a long uninterrupted seat or bearing 45 surface for the terminal portion 16 of the wire which is to be engaged by the binding-screw, which can grip even a wire of small diameter, it being understood that said wire

is extended diametrically through the post, as in Fig. 3.

To hold the wire against withdrawal from the post, and to clamp it to secure a good connection, there is provided a binding-screw 20, which is adapted to be threaded into the socket 13, and said screw has a large flat inner end, substantially coextensive with its diameter, which provides a flat, smooth, engaging surface 21 of considerable area for engagement with the wire.

The particular formation of the inner end of the binding-screw makes possible the engagement with and application of pressure to the wire along a portion of considerable length, such pressure being substantially uniform throughout the engaged portion. This engaging-portion of large diameter, extending each side of its center tends to lock the screw from readily loosening, and its end being large and flat also prevents it from cutting into and parting the wire when it is tightly screwed into the socket.

To secure the binding-post to its supporting place, the lower end of this member is reduced in diameter to form a cylindrical plug 25, which seats in a bore 26, in the supporting plate 10, and is formed with an axial bore 27, into which an attaching-screw 28 is extended, said screw being passed through suitable support 30, upon which the plate 10, is mounted. Thus, the attaching-screw 35 clamps the plate 10 and binding-post to the support. The binding-post is held against displacement from the plate 10 by swaging over the end-portion of its plug, as at 35. It will be understood that the binding-post may be otherwise secured to the plate 10, or otherwise supported.

I claim:

A binding-post comprising a body having an internally threaded socket in its outer end, provided with an unyielding side wall, and a flat bottom wall, the latter extending at right angles to the longitudinal axis of the body, there being diametrically opposed wire-receiving holes leading through the body and into the socket at the bottom thereof, the plane of the bottom of the socket being tangential to the bottom portions of the holes, and the diameter of the socket being several times greater than the diameter of the wire-receiving holes, and a binding-

- screw threaded into the socket having a flat inner end substantially co-extensive with its diameter for engagement with the terminal portion of a wire passed through the holes and extended diametrically across the bottom of the socket, the flat engaging end of said binding-screw being of a diameter several times greater than the diameter of the wire-receiving holes, so as to engage a comparatively long length of wire and to slide thereon in a transverse direction while being turned to clamp the wire, thus providing a
- 10

long frictional bearing between the screw and wire, whereby the wire is positively held from being moved about the longitudinal axis of the body and also from being withdrawn.

In testimony whereof, I have signed my name to this specification, in the presence of two subscribing witnesses.

FREDERICK W. COLE.
